Primary Examiner — Thomas Johannes*Assistant Examiner* — Jasmine Mlinarcik(74) *Attorney, Agent, or Firm* — Head, Johnson, Kachigian & Wilkinson, PC(57) **CLAIM**

The ornamental design for a fan insert for headwear, as shown and described.

DESCRIPTION

FIG. 1 is a bottom view of a fan insert for headwear; FIG. 2 is a front elevation view thereof; FIG. 3 is a side elevation view thereof; and, FIG. 4 is a top plan view thereof.

The evenly incremented broken lines represent environmental structure that form no part of the claimed design. The fan insert for headwear is a battery operated fan insert for hard hats and helmets.
